ATTORNEY.

UNITED STATES PATENT OFFICE

FRANK H. RICHTERKESSING, OF LOUISVILLE, KENTUCKY, ASSIGNOR TO CHEATHAM ELECTRIC SWITCHING DEVICE COMPANY, OF LOUISVILLE, KENTUCKY

ELECTRICALLY-OPERATED TRACK SWITCH

Application filed March 11, 1927. Serial No. 174,526.

My invention relates to electrically operated track switches operated automatically from the car.

One object of my invention is to produce a system that works "power on" or "power off" the system as hereinafter described.

Another object of my invention is to provide a system which will maintain current to the track switch operating mechanism for a period under the control of the speed of the trolley car, and always have enough time for switch operation regardless the speed of the car.

Another object of my invention is to provide a system in which independent co-operating means are employed in controlling the direction of operation of the track switch.

Another object of my invention is to provide a system in which the possibility of current flowing thru both track switch operating solenoids is eliminated.

Another object of my invention is to provide a system in which a "power off" switch operation is prevented while the system is working "power on". Another object of my invention is to provide a system in which individual electrically operated magnetic blow-out switches are used to disrupt the heavy currents of each track switch solenoid branch, the current for each branch passing thru the one controlling contact only, thereby insuring a positive opening of the circuit each time without objectional wear and destruction to the control apparatus.

A still further object of my invention is to provide a system, which will avoid the breaking of any currents by the current collector or trolley wheel which may be of sufficient magnitude to cause a destructive arc.

Another feature of my invention is to provide a safe control system embodying relays and circuits of much simpler nature than heretofore used in combination with electric track switch operation. This feature is highly desirable for production and service.

My invention resides in the new and novel combination, construction and relation of the various electrically operated switches, circuits and other parts hereinafter more fully described and disclosed in the drawings.

In the drawings accompanying my specification:

Fig. 1 is a schematic drawing showing the general arrangement of circuits usually found in an electrically operated car and which are taken account of in the operation of my invention.

Fig. 2 is a schematic drawing showing the arrangement of parts and circuits when the system is in a normal condition. Under such circumstances, however, the switch tongue may be in either of its operable positions.

My invention is intended primarily for use with those cars which are operated by means of an overhead trolley wheel or current collector W mounted on the car by means of a trolley pole T although it may be operated by cars in which current is supplied thereto by other methods. Most cars are equipped with heaters H, lights L, and air compressors F, which are connected between the trolley pole and ground. The cars are equipped with operating motors M and a controller A therefor, which is under the control of the car operator. When the controller is closed current will flow thru the motors M and this position I term "power on", and when the controller is open no current will flow through the motors and this position I term "power off". The controller A does not in any way control the current flowing thru the apparatus H, L and F, which I term the auxiliary car current. The current flowing thru the motors flows to ground G. I have arranged the system herein described so that the track switch will be operated to the "straight ahead" position when the collector W engages the trolley contactor P with "power off", and the track switch will be thrown to the curved position when the current collector engages the system using "power on". This operation of the track switch, however, may be reversed by merely transposing the connections of the track switch operating solenoids as is evident to those skilled in the art.

In the system shown in Fig. 2, the letter D represents a trolley wire or conductor. Positioned adjacent the trolley conductor is a pan or trolley contactor P provided with two

contact members E and C which are usually parallel and normally insulated from each other. The member E is electrically connected to the trolley conductor at all times, but the member C is normally insulated, but is electrically connected thereto when the collector W engages the pan or trolley contactor P. The contact members E and C are so related to the trolley conductor that when the collector engages the contact members it will be out of engagement with the trolley conductor and remain so until it is about to pass out of engagement with the pan or trolley contactor. Such arrangement of the contact members and conductor is well known to those skilled in the art.

I also employ an electrically operated track switch N provided with two solenoids SN and CN each having a connection to the ground, thru the common conductor 16.

The solenoids are provided with a reciprocating plunger J which is drawn inwardly when the solenoid SN is energized and is drawn outwardly when the solenoid CN is energized. The plunger J is connected to the switch tongue O by means of the connecting link K. I also employ an electrically operated normally open relay X provided with an operating coil KL and copper slug KLS, and a switch arm A². The coil KL and copper slug KLS are mounted on a magnet core, which is also true of the other switch coil later referred to, although a moving plunger may be substituted for the magnet core, as is well known in the art. One terminal of the coil KL is connected to the contact member E of trolley contactor P by wire E¹, and the other coil terminal is connected to the trolley conductor D by wire D¹.

It will also be noted that one coil terminal of coil KL is a common connecting point for wires 10 and 7 in addition to wire D¹. Wire 10 is connected to contact 19 which is normally open front contact relay X, and wire 7 is connected to contact 18 which is a normally open front contact on relay Z. The switch arm A² is normally in its free state, that is, not influenced by any magnetic flux, and rests against the normally closed contact 20, which is a back contact of relay X, and is connected thru wire 11 to one coil terminal of coil B on relay Z. Armature A² is connected by wire 12 to solenoid SN of track switch N.

The other relay Z that I employ has in addition to its operating coil B, a copper slug BS, and an armature A¹. Armature A¹ is connected by wire 13 to solenoid CN of track switch N. The other coil terminal of coil B is connected by wire C² to resistor R¹, which is connected to contact member C of trolley contactor P, by wire C¹.

All the relays used are provided with retarded release factors and this retardation may be brought about by various well known constructive principles. In regard to such

devices as a copper or brass slug or sleeve about the core of the coil of the relay, as indicated by KLS and BS, or it may be brought about by the spacing of the armatures with respect to their cores when in the closed position, or a combination of these, or by a dash pot arrangement, etc., or the relays may depend upon a system of time produced by a differential action of coils.

If the current collector W engages the trolley contactor P with "power off", the contact members E and C will be electrically connected and of the same potential as the trolley wire, as the contact member E is electrically connected to the trolley conductor D at all times, by wire D¹ connecting the trolley conductor D and low resistance coil KL, and wire E¹ connecting the other terminal of coil KL and contact member E. Coil KL has a very low resistance as it usually consists of 10 or 12 turns of number 6 copper wire. Relay X is a "current selective" relay, that is, a very heavy current must pass thru its operating coil KL before it can affect its armature A². As soon as the contact member C is electrically connected to the trolley conductor, through the manner just mentioned, current will flow from the trolley conductor D thru wire D¹, coil KL, wire E¹, contact member E, current collector W, contact member C, wire C¹, resistance unit R¹, wire C², coil B, wire 11, back contact 20 of relay X armature A² of relay X wire 12, solenoid SN of track switch N, wire 14, wire 16 to ground G, and the coil B of relay Z will be energized and pick up its armature A¹, that is, it will be brought into contact engagement with front contact 18. As was described the current for the operation of relay Z was taken thru the solenoid SN of the track switch N, but it should be understood that the current in this circuit is very small always less than say one ampere and will have no effect on solenoid SN that could cause an operation of the track switch, as a very heavy current is required in this solenoid circuit before a switch operation can occur. When armature A¹ was brought into contact engagement with front contact 18 and immediate flow of current resulted, feeding from the trolley conductor D, thru wire D¹, wire 7, contact 18, armature A¹, wire 13, solenoid CN of track switch N, wire 15, wire 16, to ground G. As no other resistance than that of solenoid CN is in this circuit, a very heavy current will pass thru the windings of solenoid CN, and the track switch mechanism will operate the track switch to the "straight ahead" position, as is arranged and described heretofore. Current will continue to flow to solenoid CN as long as the current collector W engages the trolley contactor P with "power off", however as soon as the current collector W disengages the trolley contactor P, the circuit of the coil B on relay Z will be opened,

and armature A¹ will return to its normal open position, and the current of the track switch solenoid circuit CN will be broken between armature A¹ and contact 18. Contact 18 is located within a magnetic blowout which is symbolically represented by A¹B. As is known to those skilled in the art of relay construction, that an arc broken within a magnetic field, known as a magnetic blowout, 10 is very quickly and easily broken, and all the deterioration of large destructive arcs is eliminated.

If the current collector initially engages the pan with "power on" the coil KL of relay 15 X will be instantly energized and pick up armature A² into engagement with contact 19, and incident to this pickup armature A² will disengage the normally closed back contact 20. As soon as armature A² engages contact 20 current will flow from the trolley conductor D, thru wire D¹, wire 10, front contact 19 of relay X, armature A² of relay X, wire 12, solenoid SN of track switch N, wire 14, wire 16, to ground G, energizing solenoid SN 25 and throwing the switch to the "curved" position, if it should be in the "straight ahead" position, but if it should be in the curved position, however, no change will occur in the position of the switch, and it will be held in 30 this position. As soon as the armature A² of relay X is closed, contact 20 is opened, as already stated, and is preferred to be in advance of the operation of relay Z, which is accomplished by the spacing of the contact 35 elements E and C of trolley contactor P. The opening of contact 20 opens the circuit of coil B of relay Z, therefore coil B cannot be energized and cause an operation of its armature A¹.

40 To sum up the operation of the system, if the car operator desires to go "straight ahead" he sets his controller to "power off" with the intention of coasting past the trolley contactor P. As soon as the current collector W 45 engages the trolley contactor P, relay Z will operate and the track switch will operate to the "straight ahead" position.

If the car operator desires to take the "curve" he will turn his controller to "power on" 50 with the intention of passing the contactor drawing power. When the current collector W engages the trolley contactor P with "power on", relay X will operate, and the track switch will be thrown to the 55 "curved" position.

There are, of course, modifications and arrangements of the parts which may be made from that shown in the above disclosure and which will still fall within the scope of my invention.

60 I claim:

1. In a switch operating system the combination of an electrically operated track switch, a trolley conductor, trolley contactor 65 to be engaged by a current collector, sep-

arate circuits for conducting current to the track switch solenoids for operating the switch in the direction desired when the current collector engages the trolley contactor with "power on" or "power off", control 70 switches to control each branch circuit individually, each switch provided with an operating coil, one switch to close the circuit for operating the track switch "straight ahead" when the system works "power off", 75 and the other switch to close the circuit for operating the track switch to the "curved" position when the system works "power on" and open the controlling circuit of the other switch to prevent operating currents being 80 applied to both operating solenoids simultaneously.

2. In a switch operating system the combination of an electrically operated track switch, a trolley conductor, trolley contactor 85 to be engaged by a current collector, separate circuits for conducting current to the track switch solenoids for operating the switch in the direction desired when the current collector engages the trolley contactor 90 with "power on" or "power off", control relays to control each branch circuit individually, each relay having an operating coil, one relay to control the circuit for operating the switch "straight ahead" when the system 95 works "power off" and the other relay to control the circuit for operating the switch to the "curved" position when the system works "power on", said latter relay having a common armature operating between two contacts, one back and one front, one contact to control the track switch solenoid circuit, and the other to control the circuit of the first 100 mentioned relay.

3. In a switch operating system the combination of an electrically operated track switch, a trolley conductor, trolley contactor to be engaged by a current collector, separate 105 circuits for conducting current to the track switch solenoids, control relays to control each branch circuit individually, each relay having an operating coil and controlling front contacts arranged within magnetic blowout arc chutes, one relay to control the circuit for operating the switch "straight ahead" when the system works "power off", and the other relay to control the circuit for operating the switch to the "curved" position when the system 110 works "power on", the latter relay being provided with a back contact permitting the 115 operation of the first mentioned relay when closed, and preventing an operation when open.

4. In a switch operating system the combination of an electrically operated track switch, a trolley conductor, trolley contactor to be engaged by a current collector, separate 120 circuits for conducting current to the track switch solenoids, control relays to control each branch circuit individually, each 125

relay having an operating coil and controlling contacts arranged within magnetic blowout arc chutes, one relay to control the circuit for operating the switch "straight ahead" when the system works "power off" and have its operating coil in series with the other track switch solenoid, the other relay to control the circuit for operating the switch to the curved position when the system works "power on" its operating coil being in series with the car circuit, the latter being provided with a back contact for controlling the first mentioned relay to prevent operating currents being applied to both track switch solenoids simultaneously.

5. In a switch operating system the combination of an electrically operated track switch, a trolley conductor, trolley contactor to be engaged by a current collector, 20 separate circuits for conducting current to the track switch solenoids, control relays to control each branch circuit individually, each relay having an operating coil and controlling contacts arranged within magnetic blow-out arc chutes, one relay to control the circuit for operating the track switch to the "straight ahead" position, and the other to control the circuit for operating the switch to the "curved" position, the latter relay having an armature common to one track switch solenoid and arranged that when its controlling means is operative it will direct operating current into the track switch solenoid, and when inoperative it will provide a 35 ground return, thru said track switch solenoid, for the first mentioned relay, by closing a circuit at its back contact.

6. A switch operating system comprising an electrically operated track switch, a trolley conductor, a trolley contactor to be engaged by a current collector, separate circuits for conducting current to the track switch solenoids for operating the switch in the direction desired when the current collector engages the trolley contactor with "power on" or "power off," control switches to control each circuit individually, each switch provided with an operating coil, one arranged to be in series with the car circuits, and the other arranged to be in series with 45 one of the solenoids, means cooperated with each switch to retard its opening providing the switch was actuated by its operating coil, so that intermittent contacts of the current collector, and trolley contactor will not interrupt the current flowing to the track switch solenoids.

7. A switch operating system comprising an electrically operated track switch, a trolley conductor, a trolley contactor to be engaged by a current collector, a branched circuit for conducting current to the track switch solenoids for operating the switch in the direction desired when the current collector engages the trolley contactor with

"power on" or "power off," control switches to control each branch circuit individually, each switch provided with an operating coil, one arranged to be in series with the car circuits, means cooperated with each switch to retard its opening providing the switch was actuated by its operating coil, so that intermittent contacts of the current collector and trolley contactor will not interrupt the current flowing to the track switch solenoids, and means for operating the first control switch before operating the second control switch.

8. In a switch operating system the combination of an electrically operated track switch, a trolley conductor, trolley contactor to be engaged by a current collector, separate circuits for conducting current to the track switch solenoids for operating the switch in the direction desired when the current collector engages the trolley contactor with "power on" or "power off," control switches to control each branch circuit individually, each switch provided with an operating coil, one switch to close the circuit for operating the track switch "straight ahead" when the system works "power off," and the other switch to close the circuit for operating the track switch to the "curved" position when the system works "power on," and open the controlling circuit of the other switch to prevent operating current being applied to both operating solenoids simultaneously, and means for operating the first control switch before operating the second switch.

9. In a switch operating system the combination of an electrically operated track switch, a trolley conductor, trolley contactor to be engaged by a current collector, separate circuits for conducting current to the track switch solenoids for operating the switch in the direction desired when the current collector engages the trolley contactor with "power on" or "power off," control relays to control each branch circuit individually, each relay having an operating coil, one relay to control the circuit for operating the switch "straight ahead" when the system works "power off" and the other relay to control the circuit for operating the switch to the "curved" position when the system works "power on" said latter relay having a common armature operating between two contacts, one back and one front, one contact to control the track switch solenoid circuit, and the other to control the circuit of the first mentioned relay, and means for operating the first control switch before operating the second control switch.

10. In a switch operating system the combination of an electrically operated track switch, a trolley conductor, trolley contactor to be engaged by a current collector, separate circuits for conducting current to the track switch solenoids, control relays to control each

- branch circuit individually, each relay having an operating coil and controlling front contacts arranged within magnetic blowout arc chutes, one relay to control the circuit for 5 operating the switch "straight ahead" when the system works "power off", and the other relay to control the circuit for operating the switch to the "curved" position when the system works "power on," the latter relay being 10 provided with a back contact permitting the operation of the first mentioned relay when closed, and preventing an operation when open, and means for operating the first control switch before operating the second control switch. 15
11. In a switch operating system the combination of an electrically operated track switch, a trolley conductor, trolley contactor to be engaged by a current collector, separate 20 circuits for conducting current to the track switch solenoids, control relays to control each branch circuit individually, each relay having an operating coil and controlling contacts arranged within magnetic blowout arc 25 chutes, one relay to control the circuit for operating the switch "straight ahead" when the system works "power off" and have its operating coil in series with the other track switch solenoid, the other relay to control 30 the circuit for operating the switch to the curved position when the system works "power on" its operating coil being in series with the car circuit, the latter being provided with a back contact for controlling the first 35 mentioned relay to prevent operating currents being applied to both track switch solenoids simultaneously, and means for operating the first control switch before operating the second control switch. 40
12. In a switch operating system the combination of an electrically operated track switch, a trolley conductor, trolley contactor to be engaged by a current collector, separate 45 circuits for conducting current to the track switch solenoids, control relays to control each branch circuit individually, each relay having an operating coil and controlling contacts arranged within magnetic blowout arc 50 chutes, one relay to control the circuit for operating the track switch to the "straight ahead" position, and the other to control the circuit for operating the switch to the "curved" position, the latter relay having an armature common to one track switch solenoid, and arranged that when its controlling 55 means is operative it will direct operative current into the track switch solenoid, and when inoperative it will provide a ground return, thru said track switch solenoid, for the first 60 mentioned relay by closing a circuit at its back contact, and means for operating the first control switch before operating the second control switch. 65
13. In a switch operating system the combination of an electrically operated track 70
- switch, a trolley conductor, trolley contactor to be engaged by a current collector, separate circuit for conducting current to the track switch solenoids, relays to control each branch circuit individually, each relay having an 75 operating coil and controlling contacts arranged within magnetic blowout arc chutes, one relay to control the "straight ahead" switch operation, and the other relay to control the "curved" switch operation, the latter relay being provided with means for opening the circuit of the first mentioned relay, when the latter relay is in an operative state, to prevent both track switch solenoids being energized at the same time, and means for operating the first control switch before operating the second control switch. 80
